(57) CLAIM

The ornamental design for a single-sole shoe as shown and described.

DESCRIPTION

The file of this patent contains at least one drawing executed in color. Copies of this patent with color drawing(s) will be provided by the Office upon request and payment of the necessary fee.

FIG. 1 is a perspective view of an embodiment of our new design for a single-sole shoe showing the claimed design as well as portions of the shoe in broken line forming no part of the claimed design;

FIG. 2 is a first side view of the design of FIG. 1;

FIG. 3 is a second side view of the design of FIG. 1;

FIG. 4 is a top view of the design of FIG. 1;

FIG. 5 is a bottom view of the design of FIG. 1;

FIG. 6 is a front view of the design of FIG. 1; and,

FIG. 7 is a back view of the design of FIG. 1.

The dashed and dotted broken lines show portions of the single-sole shoe in the above described Figures that form no part of the claimed design.
